(57) **CLAIM**

The ornamental design for an audio eyeglasses, as shown and described.

DESCRIPTION

FIG. 1 is a perspective view of an audio eyeglasses as seen from the front, top, and left side;

FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

The broken lines illustrate portions of the audio eyeglasses and form no part of the claimed design.

1 Claim, 5 Drawing Sheets
